UNITED STATES PATENT OFFICE

92,869

DESIGN FOR A TRAVELING BAG

Jesse Shwayder, Denver, Colo.

Application May 12, 1934, Serial No. 51,750

Term of patent 7 years

To all whom it may concern:

Be it known that I, JESSE SHWAYDER, a citizen of the United States of America, residing at Denver, in the county of Denver and State of Colorado, have invented a new, original, and ornamental Design for Traveling Bags, of which the following is a specification, reference being had to the accompanying drawing, forming part hereof.

Fig. 1 is a perspective view illustrating my new design for a traveling bag.

Fig. 2 is an end elevation thereof.

I claim:

The ornamental design for a traveling bag as shown.

JESSE SHWAYDER.
